UNITED STATES PATENT OFFICE.

HENRY L. PALMER, OF BROOKLYN, NEW YORK.

DESIGN FOR A CRUMB-TRAY.

SPECIFICATION forming part of Design No. 16,963, dated October 26, 1886.

Application filed September 3, 1886. Serial No. 212,645. Term of patent 14 years.

To all whom it may concern:

Be it known that I, HENRY L. PALMER, of Brooklyn, county of Kings, and State of New York, have invented and produced a new and original Design for Crumb-Trays, of which the following is a full, clear, and exact description, reference being had to the accompanying drawings, and to the letters of reference marked thereon.

10 Figure 1 is a plan or top view of my newly-designed crumb-tray, and Fig. 2 a side view or elevation thereof, these figures being deemed sufficient to fully illustrate my design.

15 In both figures like letters of reference, wherever they occur, indicate corresponding parts.

A is the bottom portion of the crumb-tray, of which the front edge, from *a* to *a*, is straight. The rear portion of the bottom is extended upwardly and outwardly, forming the back and hand piece, and is ornamented or decorated with radial flutings, as *b b*, arranged in three groups, as B C D. The side pieces join with the bottom or base and with the back, and are gracefully curved, as indicated in the plan. The upper margin of the back and hand piece is scalloped, as shown, the groups of flutings having somewhat the appearance of shells assembled or united at the rear of the bottom,

the line of union with the bottom being broken 30 and presenting an agreeable contrast with the plain surface with which they are connected. The plain surface of the bottom constitutes the major portion thereof, as seen in the illustrations.

Having now fully described my design, what I claim as new, and desire to secure by Letters Patent, is—

1. The design for a crumb-tray herein described, the same consisting of the bottom, 40 having the plain front portion, and the back and hand pieces, having the radial flutings extending to the plain portion of the bottom, substantially as shown.

2. In a design for a crumb-tray, the back 45 and hand pieces having the flutings, the same being divided into three groups, and the flutings extending radially down to the plain portion of the bottom, substantially as shown and described.

In testimony that I claim the foregoing I have hereunto set my hand in the presence of two witnesses.

HENRY L. PALMER.

Witnesses:

JOHN BUCKLER,
WORTH OSGOOD.
